UNITED STATES PATENT OFFICE.

CHARLES C. MATTOX, OF LAURELVILLE, OHIO.

ASH-PAN FOR LOCOMOTIVES.

1,057,758.

Specification of Letters Patent.

Patented Apr. 1, 1913.

Application filed March 9, 1912. Serial No. 682,679.

To all whom it may concern:

Be it known that I, CHARLES C. MATTOX, a citizen of the United States, residing at Laurelville, in the county of Hocking and State of Ohio, have invented new and useful Improvements in Ash-Pans for Locomotives, of which the following is a specification.

My invention relates to improvements in 10 ash-pans for locomotives, and the objects of my improvement are: 1st. To provide means whereby a fireman from his seat in the cab may dump ashes from the ash-pan and thereby avoid the danger of going under the 15 engine to rake the ashes out. 2nd. To provide a mechanism of few parts, simple and cheap in construction and at the same time efficient in operation. 3rd. To provide a mechanism that will dump the ashes from 20 the locomotive at any time and at any place desired. I attain these objects by the mechanisms illustrated in the accompanying drawings which form a part of my application for Letters Patent, and in which—

25 Figure 1 is a plan view of my invention; Fig. 2 is a side view of the same, and Fig. 3 is a longitudinal vertical section of the same.

In the drawings 1 represents the side plates of the ash-pan and 2 represents cross- 30 plates which join the side plates of the ash-pan together. The bottom of the ash-pan consists of a series of folding leaves 3, composed of two plates 4 and 5 hinged together. One edge of each plate 4 is adapted to rotate 35 on a transverse rod 6 which extends through and is secured in the plates 1. The free edge of each plate 5 is mounted on a transverse rod 7, which extends through slots 8 in the side plates and into connecting 40 bars 9.

On each side of the ash-pan suitable connections are made from the bars 9 to the rock arms 10 mounted on a rock shaft 11. The rock arm 10 on the left, or fireman's 45 side of the locomotive, is connected to the lower end of a hand lever 12, which extends upward into the cab and is fulcrumed to a suitable part of the locomotive framework.

It will be understood that when the lever 12 is pulled back the rods 7 connected by 50 the bars 9 will simultaneously slide forward in the slots 8, so that the leaves 4 and 5 will assume the position shown by the dotted lines in Fig. 3, and allow the ashes to drop through the openings thus formed. A reverse movement of the lever 12 will return the parts to their normal positions.

The number of folding leaves 3 in the series forming the bottom of the ash-pan may be varied according to the size of the 60 ash-pan without departing from my invention.

Having thus described my invention what I claim is:—

1. A locomotive ash-pan having side plates 65 provided with slots, a bottom composed of a series of leaves, each leaf consisting of two members hinged together, a rod to which one of said members is rotatably secured, a second rod secured to the other of said 70 members projecting through corresponding slots in said side plates and an operating mechanism connected with the projecting ends of said rods, the parts being so arranged that the two members of the leaves 75 fold up when moved into dumping position.

2. A locomotive ash-pan having side plates provided with slots, a bottom composed of a series of leaves, each leaf consisting of two members hinged together, a rod to which 80 one of said members is rotatably secured, a second rod secured to the other of said members projecting through corresponding slots in said side plates and means connected with the projecting ends of said rods for 85 operating said leaves simultaneously, the parts being so arranged that the two members of the leaves fold up when moved into dumping position.

3. A locomotive ash-pan having side plates 90 with oppositely arranged slots, a bottom comprising a series of leaves, each leaf consisting of two members hinged together, one of said members being rotatably secured, a rod secured to the other of said members 95 having its ends projecting through corre-

sponding slots and an operating mechanism engaging said projecting ends, the said parts being so arranged that the two members of the leaves fold up when moved into 5 dumping position.

In testimony whereof, I have hereunto

affixed my signature in the presence of two witnesses.

CHARLES C. MATTOX.
